DESIGN FOR A PUZZLE

Harry H. Wilson, Point Pleasant, N. J.

Application July 6, 1944, Serial No. 114,329

Term of patent 3½ years

(Cl. D34—15)

To all whom it may concern:

Be it known that I, Harry H. Wilson, a citizen of the United States, residing at Point Pleasant, county of Ocean, and State of New Jersey, have invented a new, original, and ornamental Design for a Puzzle, of which the following is a specification, reference being had to the accompanying drawing, forming a part thereof.

In said drawing

Fig. 1 is a plan view of a puzzle embodying my new design.

Fig. 2 is a transverse sectional view, taken on line 2—2 in Fig. 1.

I claim:

The ornamental design for a puzzle, as shown.

HARRY H. WILSON.
